UNITED STATES PATENT OFFICE.

JESSE AUSTIN GREENWALT, OF GALVESTON, TEXAS.

TAPE FEEDING AND CHECKING REGISTER.

1,335,576.

Specification of Letters Patent. Patented Mar. 30, 1920.

Application filed October 22, 1919. Serial No. 332,384.

To all whom it may concern:

Be it known that I, JESSE A. GREENWALT, a citizen of the United States, and a resident of Galveston, in the county of Galveston and 5 State of Texas, have invented a new and Improved Tape Feeding and Checking Register, of which the following is a full, clear, and exact description.

The present invention relates to a tape- 10 feeding and checking register, and has reference more particularly to a device of this character in which successive characterized portions of a tape are exposed through an opening in the device, with means for check- 15 ing or indicating the portions of the tape thus exposed.

The primary object of the invention is to provide a device with which a tape, including numbers or other characterized features, 20 may be checked or compared to verify the correctness of the numbers, or other characterized features of the tape.

In its preferred embodiment, the invention finds expression in a device which is 25 specially adapted for comparing the numbers of adding-machine tapes to verify the same with the figures represented on the text from which the figures were copied by the adding machine.

As heretofore practised in banking institutions and other establishments where adding and calculating machines are employed, it has been customary to verify the figures copied on the machine tape with the text, 30 to check up mistakes. The method usually resorted to in comparing these figure tapes was to have them proof read by one or two persons. This method, while satisfactory in so far as concerns the result of the comparison, 35 is impractical in that it requires either two persons' time or an undue hardship on one person. According to the preferred embodiment of the present invention, the figures of the tape may be verified with the text by a single person and without imposing a hardship on the person.

The device is illustrated in the accompanying drawings, in which—

Figure 1 is a top plan view of the device; 50 Fig. 2 is a side elevation; Fig. 3 is a cross section on the line 3—3 of Fig. 1; Fig. 4 is a longitudinal section on the line 4—4 of Fig. 1; 55 Fig. 5 is a sectional view of the tape-

checking means taken on the line 5—5 of Fig. 1;

Fig. 6 is an enlarged detail view of a part of the tape-feeding means; and

Fig. 7 is a sectional view on the line 7—7 60 of Fig. 6.

Referring now to the drawings in detail, the device preferably embodies a relatively long casing 1 providing a tape holder through which the tape A is longitudinally 65 fed, the same entering the casing or holder through an opening 2 in the slanting front wall 3, from where it passes over a suitable platen 4 positioned adjacent the face or top 5 of the casing. The tape is passed over and 70 fed through the holder by frictional contact with a rotatable roller 6 located in the opposite end of the holder and over which the tape passes to the opening 7 in the slanting back 8 of the device. To insure proper frictional contact of the tape with the roller 6, 75 a pair of oppositely-spaced friction-inducing rollers 9 and 10 are supported over the roller 6 and adapted to maintain the tape in contact with the roller 6. These rollers are 80 mounted, with freedom of rotation, on suitable spindles 11 and 12 which are, in turn, journaled in suitable bearings, the spaces between the bearings being bridged by strips 13. The friction rollers are supported over 85 the roller 6 by the levers 14 which are pivoted to the casing, as at 15, and to the strips, as at 16. Coil springs 17 are connected to the levers 14 and to the casing to maintain the friction rollers against the tape under 90 tension.

To release the friction rollers from contact with the tape, a rocking lever 17' is pivoted to the casing, as at 18, and adapted to swing about its pivot to manipulate the 95 levers 14 to raise or lower the friction rollers. The tape is fed through the holder in a step-by-step manner, to which end the roller 6 is provided with a co-axially-mounted ratchet 18, the teeth of which are 100 disposed at an angle to the axis of rotation of the ratchet, whereby they may receive a suitable ratchet 19, which is pivoted as at 20, with a hooked end 21 disposed in a position to successfully engage the ratchet 105 teeth and rotate the roller. The manipulating means for the pawl comprises a lever 22, one end of which is pivoted, as at 23, with a pivot point also provided at the pivot 20 of the pawl 19. A spring 24 con- 110

nects the pawl with the lever 22, whereby the pawl may be maintained adjacent the teeth of the ratchet, the spring also being used to return the lever 22 to normal position after it has been pressed downwardly by its key 25. A suitable escapement 26 is provided for the ratchet 18, comprising a pivoted lever having a spring tension for maintaining the roller carried by the end 10 of the lever in the pocket of one of the ratchet teeth, the roller being adapted, when the ratchet is rotated, to ride over the bevel face of the tooth and engage the next tooth.

From the above it will be seen that by 15 pressing the lever 22 downwardly by its key 25, the pawl will be caused to engage one of the teeth of the ratchet 18 and impart a downward thrust on the same, whereby the roller will be rotated one notch, and 20 when thus rotated the tape will be fed a short distance through the holder. Inasmuch as the preferred construction of the invention consists in using the device with adding-machine tapes, the ratio of the teeth 25 on the ratchet 18, as well as the throw of the pawl 19 and lever 22, should be such as to feed the tape a distance in the holder of substantially that of the space between the figures, upon one manipulation of the lever 30 22, which will be presently described.

As previously stated, the tape is fed through the holder over the platen 4 and between it to the top 5 of the casing 1. The platen is provided with suitable guides for 35 preventing lateral displacement of the tape relative to the platen; and the top 5 of the casing is provided with hinged covers 27 and 28, the covers being of a size substantially that of the width of the tape and 40 adapted to be swung on their respective hinges 29 and 30 to expose a large area of the tape so that the same may be properly adjusted relative to the platen, or for any other reason, when occasion should arise 45 to observe that portion of the tape which is beneath the cover. Provided between the covers 27 and 28 is an opening 29' which extends transversely across the face of the cover 5 and is of a length of substantially 50 that of the height of one set of figures on the tape, so that only one set of figures will be exposed through this opening at a time. When, as previously stated, the key 25 on the lever 22 is manipulated to rotate the 55 roller 6, the tape will be fed through the holder, and the ratio of the ratchet teeth together with the throw of the pawl 19 and lever 22 is such as to bring the sets of figures on the tape successively into register with 60 the opening 29. On opposite sides of the opening 29 are shutters 31 and 32, which are hinged as at 33 and 34 so that the area of the opening 29 may be increased for observing the sets of figures directly above 65 and below the exposed set of figures. Both

of these shutters are independently movable. If desirable, the covers 27 and 28 may be either independently or collectively movable, also, they may be slidably mounted to space the shutters 31 and 32 closer together or farther apart, to increase or to decrease the width of the opening 29.

As above stated, each throw of the lever 22 will expose a new set of figures through the opening 29, where they may be compared with the text. Now, inasmuch as it is desirable to indicate on the tape those sets of figures which have been compared or exposed through the opening 29, and thus check the tape, a tape-contacting finger 34' 75 is adapted to coöperate with the key 25 of the lever 22 for marking the tape adjacent each set of figures thus exposed. This finger, in its preferred form, comprises a lever pivoted as at 35 and supported by a standard 36 rotatably mounted in the top 5 of the casing. One end of the lever, normally the end which contacts with the tape, is provided with a pointed hammer 37 which, when the finger is operated, will make an 80 indentation on the tape adjacent the set of figures exposed in the opening 29, thus indicating that this set of figures have been exposed through the opening and checked. Instead of the hammer 37, any other tape-contacting means may be used which will 85 make a satisfactory check mark. The opposite end of the lever is presented in the path of a dog 38 which is pivoted as at 39 in the recess 40 of the key 25. Normally, 100 this dog projects from the recess 40, where it may have a wiping or camming contact with a tappet 41 of the lever and thus raise the hammer 37 by rocking the lever about its pivot 35. The hammer 37 is returned 105 and brought into checking contact with the tape by the spring 42 which is fixed at one end to the pivot 35 with its opposite end received between the confronting faces of the lips 43.

The operation of the machine is substantially as follows: The tape is inserted through the opening 2 and placed upon the platen 4, where it is lined up and extended over the roller 6 and through the opening 115 7 at the opposite end of the device. The knob 44 on the spindle of the roller 6 is then turned to feed the tape until the first set of figures are exposed through the opening 29', whereupon they are compared with the text, 120 and when thus compared, the key 25 is pressed down, tripping the checking hammer 37, and when further pressed downward the next set of figures on the tape will be presented in the opening 29, whereby 125 they may be compared and checked by the hammer 37 and the next set exposed, etc.

Of course, the use of the idea is in no way limited to comparing the figures of adding-machine tapes, but may be used to advan- 130

tage in other instances where it is desirable to feed a tape through a holder and in which the holder is provided with a registering opening for exposing successive characterized portions of the tape where they may be observed and checked.

While the tape has been shown and described as leaving the machine through the opening 7, it is, of course, understood that the same may instead feed over the roller 6 on the outside of the machine. This would appear desirable with a short tape. Then, again, instead of introducing the tape in the machine through the opening 2, it may be fed in the reverse direction and introduced through either the opening 7 or under friction-inducing roller 10 from the outside of the machine.

Having thus described my invention, I claim as new and desire to secure by Letters Patent:

1. In a machine of the class described, a tape holder having a registering opening therein, means for feeding a tape through the holder with successive portions thereof registering with said opening, and means co-operating with the tape-feeding means for indicating the portions of the tape thus registered.
2. In a machine of the class described, a tape holder having a registering opening therein, means for feeding a tape from one end of the machine to the other with successive portions thereof registering with said opening, and means co-operating with the tape-feeding means for indicating the portions of the tape thus registered.
3. In a machine of the class described, a

tape holder through which a tape is fed in a step-by-step manner, means for exposing successive characterized portions of the tape, and means for indicating on the tape the exposure of said portions.

4. In a machine of the character described and as set forth in claim 2, and in which the tape-feeding means comprises a rotatable platen with means for rotating the same in a step-by-step manner and in which the means for indicating the registered portions of the tape is actuated by the platen-rotating means, and comprising a pivoted tape-contacting lever adapted to normally lie in the path of the platen-rotating means.

5. A tape-feeding and checking register, comprising a tape holder having a registering opening therein, a rotatable platen at one end of the holder, means for rotating said roller in a step-by-step manner for exposing successive portions of the tape through said opening, comprising a ratchet on the roller, a pawl for engaging the teeth of said ratchet, a pivoted lever for actuating said pawl, and a tape-contacting and indicating device actuated by said pivoted lever and contacting with the tape exposed through said opening.

6. In a machine of the class described, a tape holder having means for feeding the tape in a step by step manner, and means for exposing successive characterized portions of the tape, and means operated by said tape feeding means for indicating upon the tape the exposure of said characterized portions of the tape.

JESSE AUSTIN GREENWALT.
